ATTORNEY.

UNITED STATES PATENT OFFICE.

THOMAS O. HOPKINS, OF KANSAS CITY, MISSOURI.

FASTENING DEVICE.

Application filed March 7, 1922. Serial No. 541,811. Renewed March 22, 1923.

To all whom it may concern:

Be it known that I, THOMAS O. HOPKINS, a citizen of the United States, residing at Kansas City, in the county of Jackson and 5 State of Missouri, have invented certain new and useful Improvements in Fastening Devices, of which the following is a specification.

This invention has reference to improvements in fastening devices and while not necessarily restricted to any particular form of fastening device, is particularly adapted for use in connection with collar holders.

In accordance with the invention, there is 15 provided a one-piece strand of wire, preferably spring wire, with terminal return pointed hooks and an intermediate return bend.

The curve or return bend constitutes a 20 handy means for grasping the collar holder between the thumb and first finger of the hand of the user so that the device may be attached to the collar after the tie then covering the curved portion of the device has 25 been applied so as to be embedded in the holder with its hooked end joining the adjacent flap of the collar and the return bend concealed in the device.

The terminal hooked ends of the holder as 30 well as the return bend surrounded by the holder are not in sight when the device and tie are applied to the collar, but the intermediate loop provides a convenient finger hold for applying the device both to the collar and to the tie.

The wire device forming the subject matter of this invention is so shaped as to lie in approximately one plane with the ends hooked in the collar tabs thus holding the 40 device and the tie against accidental displacement.

The invention will be best understood from consideration of the following detail description taken in connection with the 45 accompanying drawing forming part of this specification with the understanding however, that the invention is not confined to any strict conformity with the showing of the drawing, but may be changed and modified so long as such changes and modifications mark no material departure from the

salient features of the invention as expressed in the appended claim.

In the drawings:

Figure 1 is a perspective view of a negligee collar, with the invention applied. 55

Fig. 2 is a plan view of the tie holder forming the subject matter of the invention.

Referring to the drawings, there is shown a collar 1, which may be of the character 60 usually known as soft or negligee collars and may follow the general contour of such collars.

Negligee collars have a front opening 2 into which there fits an ordinary tie 3 which 65 in turn may be of the ordinary four-in-hand type or other suitable type.

The negligee collar is provided with a holding device 4, shown separately in Fig. 2 and so constructed and shaped as to engage at opposite ends into the collar 1 on opposite sides of the neck opening thereof to hold the neck opening of the collar from spreading. 70

The holding device 4 is provided with return terminal hooks 5 adapted to pierce and 75 at their extremities extend through the walls of the collar 1, where flanking the neck opening, at a location about half the height of the said neck opening. 80

Intermediate of the length of the fastening device 4, it is formed with a loop or return bend 6 which may have a sufficient spread to impart a certain amount of elasticity to the fastening device 4 so that the fastening device may be temporarily spread to facilitate the introduction of the pointed hooks 5 through the walls of the collar with the tie 3 surrounding and embedding such return bend, whereby the fastening device 4 may be embedded at the ends through the walls of the collar and the collar itself be put under a certain amount of tension causing the hooks 5 to remain engaged in the collar. 85 90 95

When the collar holder 4 is applied to the collar 1, this may be done before the tie is itself applied, ample room being then afforded for attaching the device 4 to the throat opening of the collar, after which the tie 3 may be adjusted and applied in the usual manner. 100

When it is desired to remove the tie from the collar and the collar from the person of the wearer, the fastening device 4 is readily detached by disengaging the pointed hooks 5 from the tabs of the collar and thus disengaging the tie as a whole, the tie being held to the collar by the action of the holder or fastener 4 made fast to the collar solely by the action of the hooks 5 and the embedding of the return bend 6 where surrounded by the tie itself.

The holder 4 may be very rapidly applied to the collar or disengaged therefrom and moreover may be very cheaply made so that it may be sold at a very small cost and hence will be purchased by almost anyone who desires to wear a four-in-hand or other tie with a negligee collar, with the assurance

that the invention will be readily adopted by wearers of collars and ties of the character of those shown in the drawings.

What is claimed is:

A fastening device of the class described, comprising a single, elongated piece of wire disposed in a single plane and bent intermediate upon itself into a fold or turn, with the bend continued oppositely from the central bend in a reverse direction to the first turn and then at opposite ends again returned upon themselves toward the intermediate portion and sharpened or pointed in distant relation one to the other, the device being disposed in one continuous piece.

In testimony whereof, I affix my signature hereto.

THOMAS O. HOPKINS.
